UNITED STATES PATENT OFFICE.

FRANK H. HOPLER, OF PHILADELPHIA, PENNSYLVANIA, ASSIGNOR TO
LEWIS BARNES, OF SAME PLACE.

BRIDGE.

SPECIFICATION forming part of Letters Patent No. 518,648, dated April 24, 1894.

Application filed August 3, 1893. Serial No. 482,258. (No model.)

To all whom it may concern:

Be it known that I, FRANK H. HOPLER, a citizen of the United States, residing at Philadelphia, in the county of Philadelphia and 5 State of Pennsylvania, have invented certain new and useful Improvements in Bridges, of which the following is a specification.

My invention relates to bridges, and more particularly to that class which is known as to culvert bridges, and it has for its object to provide a simple construction which can be easily and rapidly built and put together without special tools, and which shall be exceedingly strong and well-adapted to the purposes 15 for which it is intended, and to these ends my invention consists in a culvert bridge embodying the general features of construction and arrangement substantially as hereinafter more particularly pointed out.

20 Referring to the accompanying drawings, Figure 1, is a side view, a portion being cut away, showing a bridge embodying my invention; and Fig. 2 is a vertical, transverse section, on the line 2—2, Fig. 1.

25 The purposes and objects of my present invention need not be further stated, as the use of the so-called "culvert" bridge is well understood by those skilled in the art, and the requirements and desirable points to be attained in such construction are also well known, and I will now proceed to set forth 30 the manner in which I construct such bridges.

I provide longitudinal bed pieces A, A', which are preferably made of wrought iron, 35 in the form substantially as indicated most clearly in Fig. 2, that is to say, in the form of angle, bar or plate iron, the plates A', being turned up from the main body portion at an angle corresponding with the angle of the 40 sides of the bridge. I further provide what may be termed the top piece, B, of the bridge, and this is preferably in the form of a T-bar or plate of wrought iron, or similar material, the central extension B', projecting downward 45 longitudinally of the plate. These bed pieces and top piece, which are in ordinary merchantable forms usually found in the market, are then united by a series of braces, and while these braces may run vertically, I preferably arrange them at an inclination to the 50 base pieces and top piece, as this serves to

strengthen the bridge and prevent distortion, as well as to support the parts. I also preferably arrange the braces in two sets, which I term the inside braces C, and the outside 55 braces D, and these are preferably formed of flat or bar iron, and are practically all of the same shape, and they can be punched cold or otherwise, so that when they are put in position, they will all fit together and can be readily secured by bolts, rivets, or other similar means. Connected to these braces is a side wall E, and this is preferably made of iron plate, although wood or other material may be used, and as shown in the drawings, I have 60 arranged the side walls E, between the inside braces C and the outside braces D, as in this way the walls are prevented from warping or becoming distorted, and serve better to maintain the rigidity and strength of the bridge. 65 These side walls may be punched in regular order, so that the holes will correspond with the holes in the inside and outside bars, and so that the bolts or rivets may be readily placed in position, extending through the 70 braces and the side wall, and secure them all together. It will be understood that the braces and side walls are also secured by suitable rivets or otherwise, with the angle base 75 pieces A, and they are also secured to the top piece B, and I have shown a single rivet or series of rivets b, extending through the braces and side walls, and the projecting rib B' of the top piece, and it will thus be seen that all the parts are readily and firmly secured in 80 position by the smallest number of bolts or rivets.

In order to give additional strength to the bridge and prevent its spreading, I provide stay-pieces F, which unite the angle base 85 pieces at suitable intervals and hold them in proper relations.

It will thus be seen that I am enabled to provide a simple, cheap and at the same time, substantial, bridge in which all the parts may 90 be made so that they can be readily fitted in position and secured together to make a bridge of any length, and that the parts are so arranged as to attain the best results as to stability and the use of the least material for 95 the greatest strength, and while I have illustrated the preferred embodiment of my in-

vention, it is evident that the details may be varied by those skilled in the art without departing from the spirit of my invention.

What I claim is—

- 5 1. A culvert bridge, comprising the base pieces, the top piece, the braces uniting said pieces, and the side covering secured to the braces, substantially as described.
- 10 2. A culvert bridge, comprising the base pieces formed of angle iron, the top piece formed of a T-bar, the braces connected to the angle base pieces and the top T-bar, and the side plates interposed between the braces, substantially as described.

3. A culvert bridge, comprising the angle 15 bars forming the base pieces, a T-bar forming the top piece, inside and outside braces, connected to the angle base pieces and top piece, side plates interposed between the braces, and a stay piece connecting the base pieces, substantially as described.

In testimony whereof I have signed my name to this specification in the presence of two subscribing witnesses.

FRANK H. HOPLER.
